UNITED STATES PATENT OFFICE.

EDWARD ALFRED GRAHAM, OF BROCKLEY, LONDON, ENGLAND.

TELEPHONIC RECEIVER.

Application filed January 19, 1925. Serial No. 3,388.

To all whom it may concern:

Be it known that I, EDWARD ALFRED GRAHAM, a subject of the King of Great Britain and Ireland, residing at Brockley, in the 5 county of London, England, have invented Improvements in or Relating to Telephonic Receivers (for which I have filed application in Great Britain, August 29, 1923, No. 21,834), of which the following is 10 a specification.

When using wireless receivers and like apparatus embodying thermionic valves, it is necessary, in order to obtain the best result, that a telephonic receiver should be 15 selected or adapted to suit the type of valve, of the last valve in a set of valves, used. Thus, when using a low power valve, which has a high impedance, a telephonic receiver should be used having a high impedance, 20 whilst when a high power valve is used, which has a relatively low impedance, a telephonic receiver should be used having a relatively low impedance.

Now the present invention has for its object 25 to provide a telephonic receiver that can be readily adapted, at will, for use either with a low power valve or a high power valve.

For this purpose, a telephonic receiver of 30 the kind having, as usual, only two main terminals, is provided with multiple windings and with a switch device whereby the windings can be directly connected in series between the two terminals to offer a 35 high resistance when the receiver is to be used with a lower power valve, or can be connected in parallel or, it may be, if desired, in series parallel between the two terminals, to offer a lower resistance when the 40 receiver is to be used with a high power valve. A switch suitable for the purpose described can be variously constructed and be arranged within the telephone casing and be adapted to be operated from the exterior 45 thereof, as by a spindle, lever, push pin or the like, extending through the casing, or the switch may be arranged external to the casing, say at the back thereof.

In the accompanying drawings, Fig. 1 50 is a diagram illustrative of one arrangement according to the invention, Fig. 2 being an exterior view of a receiver embodying such an arrangement. Fig. 3 is a diagram of another arrangement according to the invention. 55

Referring first to Fig. 1 wherein 1 repre-

sents the diaphragm of a telephone receiver having two coils or windings 2 and 2^a, the switch comprises four spring blade contacts, *a*, *b*, *c* and *d*, arranged in pairs and a 60 rotary switch member 3 located between the two pairs. Contacts *a* and *d* are connected to the ends of winding 2 and contacts *b* and *c* to the ends of the second winding 2^a, contact *a* being connected to one terminal 4 of the 65 receiver and located in proximity to contact *b*, and contact *c* being connected to the second terminal 5 of the receiver and located in proximity to contact *d*. Contacts *b* and *d* carry conducting projections adapted to be 70 pressed against contacts *a* and *c*. The rotary switch member 3 is located between contacts *b* and *d* and comprises a metal body 75 carrying oppositely arranged projections 6 of insulating material, the said member being so shaped that in the position shown, contacts *b* and *d*, which constantly bear against it, are held away from contacts *a* and *c* by their spring action and are electrically connected together through the metal body, 80 whilst in a second position, the projections 6 of insulating material on the said body hold contacts *b* and *d* against contacts *a* and *c* respectively. The arrangement is such that in the illustrated position of the rotary 85 member 3, the receiver windings 2 and 2^a are connected in series and in the second position of the said member, they are connected in parallel. Such a switch can be made of 90 small size to admit of its being conveniently located within the receiver casing. Fig. 2 illustrates a telephone receiver A which, as to construction in general, is similar to that disclosed in the specification of my former Letters Patent No. 15369 of 1915, 7 representing in full lines a lever for the switch member 3 when occupying the position corresponding to the series connections of the coils 2 and 2^a. When the lever is moved 95 into the dotted line position, the switch member 3 occupies a position corresponding to the coils 2 and 2^a being connected in parallel. 8, 8^a are stops for the lever.

In the arrangement according to Fig. 3, 100 suitable for use with a telephonic receiver having four windings 9, the switch comprises eight switch levers 10 each associated with three contacts 11 all connected in circuit relationship as will be clearly apparent upon inspection without the necessity of a detailed description. In the first 105 position, where the levers 10 are represented

by full lines, the coils 9 are connected in series between the leads 12, 13 and on the assumption that the resistance of each coil is 500 ohms then the total resistance will equal 5 2000 ohms.

In the second position of the levers, represented by dotted lines 10^a, the left hand pair of windings are connected in series whilst the right hand pair are similarly connected in series, the two resultant pairs being however connected in parallel to afford 10 a circuit resistance of 500 ohms.

In the third position of the levers, represented by dot and dash lines 10^b, all four 15 windings are connected in parallel so that the resultant circuit resistance is 125 ohms.

The mechanical construction of such a switch may be of any suitable or known character.

20 What I claim is:—

1. In a telephonic receiver for purposes such as herein referred to, a casing having a pair of main terminals, a magnetic system in such casing, a pair of windings associated

therewith, a rotary switch member within 25 the casing, spring contact members associated with the windings and with the rotary switch member, a lever member outside the casing for operating the rotary switch member and stops for such lever adapted to ensure that in one position the windings are connected in series between the main terminals and in another position in parallel therebetween.

2. In a telephonic receiver for purposes 35 such as herein referred to, a casing having a pair of main terminals, a magnetic system in said casing, a plurality of windings associated therewith, a rotary switch member within the casing and a lever for actuating said switch member whereby the latter may be moved to effect alternative connection of the windings in series and in parallel between the terminals.

Signed at London England this seventh 45 day of January 1925.

EDWARD ALFRED GRAHAM.
